TACK BUTTON

Max Emsig, Brooklyn, N. Y.

Application September 27, 1935, Serial No. 42,488

5 Claims. (Cl. 24—95)

This invention relates to buttons, more particularly that type of button known as tack buttons which are secured to the cloth by passing a tack or rivet through the cloth into the front 5 of the button, the end of the tack being then spread or clinched within the button to secure it to the cloth.

It is the main object of the invention to provide a button of the character as indicated which 10 shall be efficient in operation, easy to install in place upon the goods and shall be of rugged and firm construction.

A further and more specific object of the invention is to provide an increased and more 15 stable contacting area between the housing portion and the anvil portion.

A further object of the invention is to provide a button of the character described wherein the anvil portion is of such a character that it may 20 be readily adapted to any height of housing and still maintain its clinching or spreading qualities without altering the general design of the button.

Other and ancillary objects of the invention 25 will appear hereinafter.

25 In the accompanying drawing which illustrates the invention:

Fig. 1 is a perspective view of a button embodying the invention in place upon a cloth, the latter being shown in section.

30 Fig. 2 is an enlarged axial section on the line 2—2 of Fig. 1.

Fig. 3 is an exploded view showing in perspective the parts from which the button is formed; and

35 Fig. 4 is a perspective view of a modified form of tack or rivet.

Referring to the drawing, the button comprises a front 1, an anvil 2, a housing 3 and a tack or rivet 4.

40 The front comprises a flat portion 5 having the marginal flange 6 at right angles thereto.

The anvil portion comprises the central projection comprising the cylindrical part 7 adjacent the base comprising the marginal portion or 45 flange 8, the central projection having the conical end 9.

The housing part 3 comprises the housing portion 10 having the marginal portion or flange 11 at right angles thereto, the housing portion 50 10 being open at 12 at one end and having the smaller opening 13 at its other end.

The tack 4 comprises the head 14 from which extends the shank 15 in the end of which is the transverse slot 16 forming the prongs 17.

55 In assembling the button, the flanges 8 and

11 of the anvil and housing are placed within the front 1, and the edge of the flange 6 has its edge peened over the edges of the flanges 8 and 11 so that they are securely held together. It will be observed that the flanges 11 and 8 provide flat engaging surfaces between the housing and anvil whereby these two parts have a broad, stable and firm bearing on each other, and the flat surfaced broad bearing between the anvil and the flat face 5 of the front produces a firm 10 and secure engagement between the anvil and housing parts and the front so that when they are secured together by the peening over of the edge 18 on the front a rugged and firm construction is obtained.

15 In assembling the parts as described, it will be seen that the central projection of the anvil telescopes within the housing portion 10 with a clearance 19 between it and the housing. Further, the provision of the conical spreading end 20 on this projection with a cylindrical portion 7 between the conical portion and the base of the anvil, provides a construction whereby the desired inclination of the conical portion may be made such as is best to produce the best results 25 in spreading the tack, and this may be located at any point desired within the housing by making the cylindrical portion 7 of the projection of the desired length. Without such a cylindrical portion a change in the distance of the 30 spreading point of the projection from the base of the anvil would necessitate a change in the inclination of the comb within the permissible limits of the size of the button.

The anvil front and housing having been assembled as described (and as shown in Fig. 2) the button is secured to the cloth 20 by inserting the tack as shown in Fig. 3 through the cloth, with its head 14 on the opposite side thereof from the button, and this pronged end entering through the hole 13 of the housing and the point of the projection 9 engaging in the slot 16 between the prongs of the tack. The tack and the remainder of the button are then forced together when the prong 17 of the tack would be spread as shown in Fig. 2 when the housing and its secured parts will be securely clamped to the cloth. The parts are preferably of such dimensions that in securing the button to the cloth as described the prong 17 will be spread to such an extent 50 as to bite into the walls of the housing portion 10. The firmness and stability of the securing of the button is thereby enhanced.

If desired, the anvil may be made hollow as indicated by the dotted line 22 in Fig. 2.

Referring to the modified form of tack as shown in Fig. 4, there is therein shown a tack which instead of having its shank slotted to form prongs as shown in Figs. 2 and 3, the shank 15' of the tack of Fig. 4 has a central bore 21. When this tack is used in an assembly such as shown in Fig. 2 the point of the anvil cone 9 enters within the bore 21 and the portions of the shank surrounding the bore are spread outwardly, as the tack is forced toward the anvil, in much the same manner as the prongs 17 are spread, so that the button is secured to the cloth in a similar manner.

While the invention has been illustrated in what are considered its best applications, it may be embodied in other structures without departing from its spirit and is not therefore limited to the structures shown in the drawing.

What I claim is:—

- 20 1. In a button, the combination with a front comprising a flat portion and a marginal flange at right angles thereto, of a back comprising a central cylindrical housing and a substantially flat marginal flange extending outwardly at right angles to said housing, said housing having a hole for the entrance of a portion of an anvil at one end and a smaller preformed central hole for the entrance of a tack at its other end, an anvil having a central tack spreading projection and a flat peripheral portion substantially co-extensive radially with the said flange of said back, and a tack, the flat marginal portions of said front and back lying flat against opposite sides of said anvil and secured together by said front, the said flat portions of said front and back lying within the said marginal flange of said front and secured by the inwardly bent edge of said marginal flange of the front, said projection on said anvil extending within said housing, the side walls of the projection being spaced from the side walls of the housing and the tack entering the said housing through its said smaller hole and spread by said anvil, the spread portions of said tack being entirely within said housing.
- 45 2. In a button, the combination with a front comprising a flat portion and a marginal flange at right angles thereto, of a back comprising a central housing and a substantially flat marginal flange extending at right angles to said housing, said housing having a hole for the entrance of a portion of an anvil at one end and a smaller preformed central hole for the entrance of a tack at its other end, an anvil having a central tack spreading projection and a flat peripheral portion substantially co-extensive radially with the said flange of said back, and a tack, the flat marginal portions of said front and back lying flat against opposite sides of said anvil and secured together by said front, the said flat portions of said front and back lying within said marginal flange of said front and secured by the inwardly bent edge of said marginal flange of the front, said projection on said anvil extending within said housing, the side walls of the projection being spaced from the side walls of the housing and the tack entering the said housing through its said smaller hole and spread by said anvil, the spread portions of the tack biting into the walls of said housing.
- 70 3. In a button, the combination with a front comprising a flat portion and a marginal flange at right angles thereto, of a back comprising a central housing and a substantially flat marginal flange extending at right angles to said housing, said housing having a hole for the entrance of a portion of an anvil at one end and a smaller

preformed central hole for the entrance of a tack at its other end, an anvil having a central tack spreading projection and a flat peripheral portion substantially co-extensive radially with the said flange of said back, and a tack, the flat marginal portions of said front and back lying flat against opposite sides of said anvil and secured together by said front, the said flat portions of said front and back lying within the said marginal flange of said front and secured by the inwardly bent edge of said marginal flange of the front, said projection on said anvil extending within said housing, the side walls of the projections being spaced from the side walls of the housing and the tack entering the said housing through its said smaller hole and spread by said anvil, said anvil projection being substantially cylindrical adjacent its base and having a tapered end portion.

4. In a button, the combination with a front comprising a flat portion and a marginal flange at right angles thereto, of a back comprising a central cylindrical housing and a substantially flat marginal flange extending outwardly at right angles to said housing, said housing having a hole for the entrance of a portion of an anvil at one end and a smaller preformed central hole for the entrance of a tack at its other end, an anvil having a central tack spreading projection and a flat peripheral portion substantially co-extensive radially with the said flange of said back, and a tack, the flat marginal portions of said front and back lying flat against opposite sides of said anvil and secured together by said front, the said flat portions of said front and back lying within the said marginal flange of said front and secured by the inwardly bent edge of said marginal flange of the front, said projection on said anvil extending within said housing, the side walls of the projection being spaced from the side walls of the housing and the tack entering the said housing through its said smaller hole and spread by said anvil, the spread portion of said tack being entirely within said housing and in the space between the side walls of the projection and of the housing.

5. In a button, the combination with a front comprising a flat portion and a marginal flange at right angles thereto, of a back comprising a central housing and a substantially flat marginal flange extending at right angles to said housing, said housing having a hole for the entrance of a portion of an anvil at one end and a smaller preformed central hole for the entrance of a tack at its other end, an anvil having a central tack spreading projection and a flat peripheral portion substantially co-extensive radially with the said flange of said back, and a tack, the flat marginal portions of said front and back lying flat against opposite sides of said anvil and secured together by said front, the said flat portions of said front and back lying within the said marginal flange of said front and secured by the inwardly bent edge of said marginal flange of the front, said projection on said anvil extending within said housing, the side walls of the projections being spaced from the side walls of the housing and the tack entering the said housing through its said smaller hole and spread by said anvil, said anvil projection being substantially cylindrical adjacent its base and having a tapered end portion, the spread portion of the tack being within said housing.
